UNITED STATES PATENT OFFICE

CECIL WHEATLEY STANCLIFFE, OF ALDWYCH, LONDON, ENGLAND

BOILER AND FURNACE

Application filed April 13, 1928, Serial No. 269,859, and in Great Britain April 22, 1927.

This invention relates to control apparatus for boilers and furnaces, and has for its principal object to provide an improved apparatus which will avoid the uncertainties attendant upon electro-magnetic means previously proposed and will enable the supply of fuel air exhaust gases or other similar quantities to be controlled automatically by mechanical means in accordance with the variation of steam pressure or other variable physical quantity of the boiler or furnace. The invention is particularly applicable, though not restricted to controlling the supply of fuel and air to a boiler and it is to be understood that wherever I refer in this specification to the fuel control means I mean to cover the case of solid or liquid fuel supply, or air supply or both fuel and air supply together.

A further object of the invention is to provide a control apparatus comprising a plunger which is subjected to a pressure which is a function of the steam pressure or other variable physical quantity of the boiler or furnace, and moves against a resistance which increases in a predetermined manner so that the position of the plunger depends upon the boiler pressure or other controlling quantity, and the movement of the plunger is communicated by improved independently driven mechanical means to the supply control means at one or more stations.

A further object of the invention is to provide a control apparatus in which a main control member moves by amounts which are functions of the steam pressure or other boiler condition and governs the movement of a supply control device by mechanism which enables the movement allowed to the control device corresponding to a given movement of the main control member to be adjusted at a stage of its movement without affecting the movement allowed to the control device for an equal movement of the main control member at other stages of its movement.

A further object is to provide at the fuel control stations means for imposing an adjustment upon the movement transmitted from the plunger.

With these and other objects in view the invention consists in the novel arrangements and combinations hereinafter described in detail, the novel features whereof are set out in the appended claims.

In the accompanying drawings which illustrate the invention in a diagrammatic manner,

Fig. 1 represents in elevation the preferred form of main control plunger apparatus, the position of the plunger of which is automatically controlled by the steam pressure in the boiler.

Fig. 2 represents in elevation the supplementary damper control apparatus operated from the main control plunger.

Fig. 3 represents in elevation the supplementary fuel feed control apparatus operated from the main control plunger.

Referring first to Fig. 1 of the drawings a plunger A works in a cylinder B full of oil which communicates with a chamber C having water at the bottom and oil on the top; the lower part of this chamber is connected by a pipe D to the boiler.

The plunger carries a weight E at its upper end which is guided between frame members a. Upon ledges b on this frame are mounted a series of loose weights F, which may be of equal or varying weight and may be at equal or unequal distances apart. When the difference of pressure on the two sides of the piston A—depending upon the steam pressure in the boiler—exceeds the total weight of plunger and weight E, the plunger rises until it engages the lowest weight F. It then stops unless the steam pressure is sufficient to lift this weight whereupon the plunger rises further until it encounters the next weight and so on. The ledges b are arranged in staggered relation to each other and the weights have slots cut in their sides so that each weight while resting on its appropriate ledge will be able to pass freely above the upper ledges.

The position of the plunger controls the position of a control cable G and this cable is carried by a shaft H driven by an independent motor so that the piston need not be able to have sufficient power to operate the cable but acts as a relay.

The drive mechanism is as follows:—A motor I drives a shaft J through a bevel gear J¹ and this through a worm J² and wheel J³ keeps the plunger constantly in rotation; this helps to minimize inertia effects due to gland friction and the like. To permit this rotation to occur without rotation of the weight E, a thrust bearing E¹ is provided.

- Above and below the worm wheel J³ pinions J⁴, J⁵ of equal diameter are carried. 10 These pinions are adapted alternatively to engage pinions H⁴, H⁵ carried by bevel pinions H⁶, H⁷ each of which engage a bevel pinion H⁸; these bevel pinions form a crown bevel train and are carried in a bracket H² which 15 slides on a guide rod K and through which the shaft H passes. The pinion H⁶ is keyed or splined to the shaft H and the pinion H⁷ is loose thereon and the upper portion of the shaft is screw threaded and passes through 20 a nut L and is connected to the cable G by a swivel H¹.

Now suppose that the plunger rises; the pinion J⁴ will then engage the pinion H⁴ and the shaft H will thus rotate and due to the 25 engagement with the nut L will rise also. The shaft H will stop rotation when the plunger stops because the pinion H⁴ will then rise clear of the pinion J⁴.

If the plunger falls, the pinion J⁵ will move 30 into engagement with the pinion H⁵ and through the loose bevel pinions H⁷, H⁸ will drive the bevel pinion H⁶ in the reverse direction thus causing the shaft H to fall; when 35 the pinion ceases to fall the shaft H will stop because the pinion H⁵ will pass out of engagement with the pinion J⁵.

The plunger thus acts as a relay governing the position of the shaft H and thus of the 40 control cable G.

The main control cable G is connected in any suitable manner with a number of supplementary control stations. The main cable 45 may for instance be connected to a shaft upon which are carried a number of supplementary control cables which will move in unison with the main control cable, and by employing pulleys of varying sizes the motion may be geared up or down.

It is desirable that at each supplementary 50 control station we may have a control apparatus which may be adjusted independently of the other controls. This is effected by connecting the supplementary control cable M, Fig. 2, to a series of weights Q, in number 55 equal to those of the main control apparatus and at the same distance apart if the cable M moves at the same speed as the main cable G, and at corresponding distances apart if the 60 cable motion is geared up or down.

The weights are connected by chains e and 65 are suspended by chains d from a fixed bracket O; the cable M passes through this bracket and through the weights and is connected at the end to an abutment m which is adapted

to engage under the lowermost weight Q and to lift it. When the cable has moved sufficiently the other weights Q will be picked up in turn. The weights Q are connected by cables R₁, R₂, R₃, R₄ to a counterweighted lever S attached to the damper P of a flue T. 70

The length of each of these chains R₁—R₄ can be adjusted so that the position of the damper corresponding to any given over pressure of steam may be varied due to particular circumstances such as flue gas analysis; any convenient adjustment means may be employed for the length of chain. 75

In the position shown on the drawings the damper is full open, the lowest weight Q is about to be lifted and the chain R₄ is taut; the length of the chain R₄ however can be adjusted independently of the main control apparatus and thus the position of the damper varied. 80

When the abutment m rises to bring the two lowest weights Q in contact the chain R₄ will have become slack and the damper will be controlled by the cable R₃ which will then be slack, and so on for other positions. 85

The apparatus illustrated in Fig. 3 of the drawings for the fuel control is similar in all respects with that previously described except that the chains R₁—R₄ are connected to a drum U connected to a rheostat lever V by a cable u passing over a pulley v and carrying a counterweight W. Each rheostat governs the speed of a motor or other device which determines the rate of fuel to each boiler, and thus each rheostat can by means of the chains have any desired adjustment imposed upon that given by the main control apparatus. 90

It is to be understood that the invention is not restricted to the exact details shown and described but embraces such modifications as come within the ambit of the accompanying claims. 100

I claim:—

1. Apparatus for controlling boilers and furnaces comprising a plunger subjected to a pressure which is a function of the steam pressure or other controlling quantity, a series of weights at spaced intervals each normally resting against abutments, means for causing said weights successively to resist the movement of said plunger, a power driven shaft, a supplementary shaft having gearing connection with said shaft, means for throwing said connection out of operation when the plunger is stationary, and means for communicating the movement of said supplementary shaft to the fuel control means. 115

2. In boiler and furnace control, apparatus, a plunger, means for causing said plunger to move to a position which is a function of the steam pressure or other controlling quantity, two parallel power driven pinions caused to move axially synchronously with said plunger, a transmission shaft, 120

125

130

two parallel pinions on said transmission shaft slightly farther apart than the said power driven pinions and adapted to engage therewith one at a time, one of said pinions being free on said transmission shaft and the other being splined thereto, bevel wheels connecting said pinions, means for causing said transmission shaft to move axially and means for causing said pinions carried thereby to move with the shaft and thus to move out of engagement with the power driven pinion when axial movement of the latter ceases.

3. Apparatus for controlling boilers and furnaces comprising a main control member moved by distances which are functions of the steam pressure or other controlling quantity, a secondary control means comprising a series of weights successively brought into operation by successive stepped movements of the main control member, a supply control device, and a flexible member of variable length connecting each weight to the supply control device.

4. Apparatus for controlling boilers and furnaces comprising in combination a control means which moves by distances which are functions of boiler pressure or other boiler condition, a supply control device, and a plurality of flexible members connecting the supply control device to the control means and successively coming into operation as the control means moves into successive positions.

5. Apparatus for controlling boilers and furnaces comprising in combination a mechanically operated control means which moves by distances which are functions of boiler pressure or other boiler condition, a supply control device, a series of independent mechanical connectors controlling the movement of the supply control device at successive steps of the movement of the control means, and mechanical means for varying the movement of the supply control device for one step of the movement of the control means without affecting the movement of the supply control device for other steps of the movement of the control means.

6. Apparatus for controlling boilers and furnaces comprising a main control member moved by distances which are functions of the steam pressure or other controlling quantity, a plurality of secondary control means each operatively connected to the main control member, means for connecting by mechanical means each secondary control means to a supply control device, and adjustable means whereby the movement given to any one supply control device for any given movement of the main control member throughout its range of movement may be varied without affecting the movement given to any other supply control device.

7. Apparatus for controlling boiler fur-

naces in which a main control member which is caused to move by amounts which are functions of the steam pressure or other boiler condition communicates its movement to a series of weights suspended from a fixed support one above the other and connected to each other by chains or cables, said weights being connected to a supply control device.

8. Apparatus for controlling boilers and furnaces in which a main control member moved by distances which are functions of the steam pressure or other controlling quantity communicates its movement to a series of weights each of which is connected to a supply control device by a chain or cable the length of which is adjustable.

9. Apparatus for controlling boilers and furnaces comprising a plunger responsive to a boiler condition, a series of resistances successively engaged by movement of the plunger, a motor carried by said plunger, gearing for rotating said plunger from said motor, a control member, and gearing driven by said motor and causing the control member to follow the movement of the plunger.

10. Apparatus for controlling boilers and furnaces comprising a main control member moved by distances which are functions of the steam pressure or other controlling quantity, a supply control device, a plurality of secondary control members adapted to be successively actuated by the main control member, separate mechanical connections between said secondary control members and said supply control device, and means for varying the effective length of said mechanical connections.

In testimony whereof I affix my signature.
CECIL WHEATLEY STANCLIFFE.
